UNITED STATES PATENT OFFICE.

LEE B. FOSTER, OF PITTSBURGH, PENNSYLVANIA, ASSIGNOR TO THE PARELLA CORPORATION, OF PITTSBURGH, PENNSYLVANIA, A CORPORATION OF PENNSYLVANIA.

UMBRELLA.

Application filed May 22, 1928. Serial No. 279,652.

The invention relates to temporary or emergency umbrellas, and especially to those having a body structure formed from self form-sustaining material, the object being to 5 provide an umbrella of the type referred to with flap-like supporting means connected to the umbrella to hang down freely in umbrella-supporting position and to be swung against the side when not in use.

10 The umbrella according to the invention comprises a conical, umbrella-like body structure formed from self form-sustaining material, and flap-like supporting means connected at one end to the underside thereof 15 at a point removed from its apex. The body structure is preferably formed from a single sheet of suitable material, by forming a slit inwardly from the edge and overlapping the material adjacent thereto to form a conical 20 structure, the overlapping edges being connected in any suitable manner. In the preferred form the supporting means comprise strips of semi-rigid material connected to the under side of the structure at a point intermediate the edge and the apex, the strips 25 being hinged at their inner connected ends so that they may hang freely in umbrella-supporting position, or may be swung against the side when not in use to facilitate packing, 30 shippage, or storage. Preferably two diametrically opposed strips are used.

The preferred embodiment of the invention is illustrated in the accompanying drawings, in which Fig. 1 is a plan view of a sheet 35 of material prepared for forming an umbrella; Fig. 2 an elevation of an umbrella made from the sheet shown in Fig. 1; Fig. 3 a detached supporting member shown to enlarged scale; and Fig. 4 an enlarged sectional view showing one manner of connecting a 40 supporting member.

Having reference to the drawings, the umbrella comprises a body portion 1, Fig. 2, and depending supporting members 2 connected thereto. The body is formed from a sheet 3 of a suitable semi-rigid material possessing sufficient rigidity to make it self form-sustaining when shaped, and sufficiently waterproofed, such as paraffined or cal- 45 lendered cardboard. Although the structure 50 may be shaped in various ways, it is preferred to do this by forming a slit 4, Fig. 1, in a circular sheet 3, extending from the edge substantially to the center, and lapping a portion A over the other edge portion B to form

a conical umbrella-like structure of the desired proportions, such as that shown in Fig. 2. The overlapped material is connected together in any appropriate manner, as by stitching, gluing, and the like, and the structure thus formed requires no auxiliary reinforcement to maintain it in shape.

60 The supporting means used is preferably formed from strips of semi-rigid material, such as that used in making the body structure. As shown in Fig. 2, it is preferred to use two such members each connected at one end to the body structure at a point removed from its apex. The form and dimensions of 65 these members may vary, as may the manner of connecting them, provided adequate strength is secured, the preferred manner of connecting them being shown in Figs. 2 and 4. One end of each strip 2 is bent to provide 70 a foot or flange 5, which is glued or stitched to the underside of the body 1 at a point intermediate the edge and the apex, and strips 75 of adhesive material 6, such as gummed paper, are placed over the flange 5 and in the angle on the opposite side to further 80 strengthen the joint.

By this construction the supporting members hang freely in umbrella-supporting position in a manner similar to that of the usual rigid umbrella handle, or they may be swung 85 against the side when not in use so that the umbrellas may be readily stacked for storage or shipment. The hinge-action may, if desired be furthered by providing a line of 90 weakness 7 in the strip. Where two strips are used, they are preferably disposed diametrically opposite each other at equal distances from the apex of body 1, the distance between them being such that when held over the head, the strips depend on each side thereof. By this construction, the umbrella may 95 be held in proper position by grasping one strip in each hand, or by grasping both in one hand, in which case the strips will converge, and can be held readily for adequate protection. The umbrellas are especially suitable 100 for distribution to persons congregated outdoors, as at fairs, athletic events, or other gatherings, and advertising matter may be printed on them so that they provide an excellent and very inexpensive publicity medium for free distribution, or for sale at a 105 small sum.

According to the provisions of the patent statutes, I have explained the principle and 110

operation of my invention, and have illustrated and described what I now consider to represent its best embodiment. However, I desire to have it understood that, within the scope of the appended claims, the invention may be practiced otherwise than as specifically illustrated and described.

I claim:

1. An emergency umbrella comprising a body structure of self form-sustaining material, and a flap-like supporting member connected at one end to the underside of said structure at a point removed from its apex, said member hanging freely from said point of connection when in umbrella-supporting position and adapted to swing against the body of the umbrella when not in use.
2. An emergency umbrella consisting of a single sheet of semi-rigid material formed into a self form-sustaining umbrella-like structure, and a pair of diametrically opposed flap-like supporting members formed from strips of semi-rigid material connected at their inner ends to the underside of said structure at points equally removed from its apex, said members hanging freely from their points of connection when in umbrella-supporting position and adapted to swing against the body of the umbrella when not in use.

members connected at their inner ends to the underside of said structure at points intermediate its edge and apex, said members hanging freely from their points of connection when in umbrella-supporting position and adapted to swing against the body of the umbrella when not in use.

3. An emergency umbrella consisting of a single sheet of semi-rigid material formed into a self form-sustaining umbrella-like structure, and a pair of diametrically opposed flap-like supporting members formed from strips of semi-rigid material connected at their inner ends to the underside of said structure at points equally removed from its apex, said members hanging freely from their points of connection when in umbrella-supporting position and adapted to swing against the body of the umbrella when not in use.

In testimony whereof, I sign my name.
LEE B. FOSTER.
